O. W. BROWN

COCONUT SEVERING DEVICE

Filed April 9, 1927

Inventor

Oswell W. Brown

By Clarence O'Brien
Attorney

UNITED STATES PATENT OFFICE.

ORVILL W. BROWN, OF ROMULUS, NEW YORK.

COCONUT-SEVERING DEVICE.

Application filed April 9, 1927. Serial No. 182,431.

The present invention relates to a device especially constructed for severing the fibrous shell of a coconut from the meat containing kernels or nuts.

5 The invention has more particular reference to a device of this class which has been especially prepared to remove the fibrous shells in an easy and orderly manner.

The invention is characterized by such 10 features as simplicity in construction, ease of manufacture, strength and durability, convenience and compactness and efficiency in operation.

Briefly, the invention has reference to a 15 stand including a base ring upon which upstanding cutters are hingedly mounted, the cutting edges of the cutters being arranged for penetrating the shell and removing it in segments in an expeditious manner.

20 In the drawings:—

Figure 1 is a side elevation of the complete device.

Fig. 2 is a top plan view of the same, and

25 Fig. 3 is a fragmentary sectional and elevational view.

In the drawings, the reference character 1 designates generally the stand which comprises, as before indicated, a base ring 2 of appropriate diameter fastened to supporting legs 3. Hingedly connected to this ring as at 4 are the upstanding cutters generally indicated at 5. Ordinarily three of these cutters will suffice for efficient operation. They are arranged at equi-distant, circumferentially spaced points, and each one is formed from a metal plate of channel-shaped cross section.

The hinged lower end is open while the side walls of the upper end converge toward 40 each other and emerge into cutting edges 6. The side walls are preferably riveted together for strength and the cutting edges are inclined downwardly and outwardly to provide penetrating points 7. These cutters are movable toward each other and swingable in an outward direction as indicated in dotted lines against the tension of retaining springs 8.

Each spring comprises a flat metal strip having its lower end curved upwardly and 50 riveted to the hinged connection. The upper end is riveted to the upper intermediate portion of the cutter.

The complete device is about waist-high and is usually set on a strong supporting 55 surface. Then an untreated coconut is set down upon the penetrating points for severing of the fibrous outer shell. While the nut is in this position, the operator takes a mallet, strikes a blow upon the coconut, 60 whereupon the point penetrates the shell and severs the same into segments which drop off.

The kernel drops down in between the cutters whereupon it is removed, the cutters 65 being hingedly mounted and held in place by springs, it is obvious that they accommodate different sizes of coconuts.

By considering the description in connection with the drawing, a clear understanding of the invention will doubtless be had. Therefore, a more lengthy description is thought unnecessary.

Minor changes coming within the scope of the invention claimed and including such 75 departures as in shape, size and re-arrangement may be resorted to if desired.

Having thus described my invention, what I claim as new is:—

In a structure of the class described, a 80 stand including supporting legs and a base ring, a plurality of upstanding cutters hingedly connected to said ring at circumferentially spaced points, springs connected at one end with the cutters and at the opposite 85 ends with said rings, said cutters being swingable in an outward direction against the tension of said springs, each cutter being of hollow construction and provided with downwardly and outwardly inclined cutting edge terminating at its inner end in a single vertical cutting edge sloping to a penetrating point.

In testimony whereof I affix my signature.

ORVILL W. BROWN.
